John F. Aytell Geneva N.Y.

8024

Setters Patent February 18. 1834.

The schedule referred to in this Setters Patent and making part of the same containing a description in the words of the said John F. Aytell briefly of his improvement in the mode of making thrashing Machines.

To all persons to whom these Presents shall come, John F. Aytell of the Village of Geneva in the County of Ontario and State of New York sends his best greetings.

Be it known that I the said John F. Aytell have invented and in the manner of a thrashed machine and applied to use, a new and useful improvement in the mode of making thrashing Machines, the parts of the same to be made of cast or wrought iron. The advantage of having the same made of iron, is, it being stronger more durable, less liable to get out of repair, more steady and regular in its operations & although of greater strength of itself and more compact, takes up less room and is, more easily transported from place to place if required by having the sides in one piece of metal with the grooves and flanges forming a part makes the whole firm and impossible for it to get out of place.

The small compass of the machine, the durability of its parts, the facility with which it can be stored and put in operation & the low price for which it can be obtained gives the said thrashing machine which is called a Single Cast iron Thrashing Machine, a decided advantage over any other thrashing machine, two in one.

The mode of said machine in the Patent Office of the United States at Washington as well as the plates hereto attached & the lettering of the same with the Specification thereof given below will particularly set forth and describe the different parts of the machine, the distinct operation and use of each part & the effect produced when put in operation.

The improvement claimed is in making the sides of the machine of iron instead of wood & other materials & for the manner in which the same is put together.

The first is an upright side piece of the machine lettered and described as follows:

Letter *c* an upright side plate of the Machine made of Cast iron the end of this plate being raised forming the legs of the Machine as represented by letter *p. 11* the top of the plate forming a flange as represented by letter *b* which supports the Cap of the machine letter *f*. *b* a brace or rest attached to the main plate by bolts or screws supporting the out end of the journal of the main wheel and letter *a* which the steam plate the main wheel moves the journal of the main wheel being confined on the rest by a coupling as represented by *p. 11* in plate C to 4 the brace or rest *a* more plainly represented in plate C to 4 by letter *b* the main article of machine *M* working into journal *M* wheel *b* a universal joint attached to journal of main wheel connecting the machine with the pony wheel to be propelled by the side of the Cap of machine made of iron *c* which can be taken off at pleasure *g. g.* pins attached to the Cap passing thro' the flange *b* and confining Cap to main plate in the top part of main side plate forming a flange projecting to the front thro' which pins *g. g. p. 11*

in view bolts or screws connecting the machine together &c &c depicting
connecting the journals of pinions, wheel to said plate Plate C16 2 and view
of the machine. Setting a. a. edge of the side plates forming the legs which
support the machine - b. the frame or rest of the main wheel. d. the
universal joint connecting the machine with the power applied to latter. M.
a. a. line of shafts. e. e. e. e. e. the teeth or spikes in the cylinder and concave of machine
as these more clearly appear in plate C16 3. f. the cap of the machine covered
with sheet iron i. e. the bolts or screws connecting side plates with trunnions j. k. m.
lower part of frame between side plates & the upper board joined to the con-
cave let into side plates by means of grooves in the side plate ^{as before} ~~as before~~
marked by letters n. o. in plate C16 3. l. pinion wheel passing into main wheel
& cylinder k. m. in plate C16 3. m. the top of frame between
side plates in line shaft Plate C16 3 an upright inside view of side plates
Setting a. the side plate b. an end view of cylinder & d. d. C16 3 grooves in which
the pinion concave ends. Holes are placed, e. e. e. e. e. the teeth or spikes fixed in
concave and on cylinder which thrash the grain of the journal of the cylinder
i.e. bolts or screws holes to no. plates cast on plate forming grooves as represented
in plate C16 2 by letters k. o. o. Plate C16 4 a. front or top view of the side plate.

nest, main wheel, universal joint line shaft, &c. Set in a top of plate h. the
brace or rear supporting journal of main wheel, &c. the main wheel h. and
universal joint h. by bolts or screws. Connecting brace nest with side plate
of machine - a line shaft & coupling connecting journal of main wheel to
the brace or nest. Testimony that the above is a true specification of my
said improvement as above described called "Cylindrical Cast Iron Thrust
ring Machine." I have hereto set my hand this 23rd day of June 1833
